(57) **CLAIM**

The ornamental design for a bottle carrier with graspable loop, as shown and described.

DESCRIPTION

FIG. 1 is a top front perspective view of an ornamental design for a bottle carrier with graspable loop according to the present invention.

FIG. 2 is a bottom rear perspective view thereof.

FIG. 3 is a top view thereof.

FIG. 4 is a front view thereof, the back view being a mirror image thereof.

FIG. 5 is a front view thereof, additionally illustrating in dashed lines a hand lifting the bottle carrier by the graspable loops, as well as bottles secured within the bottle carrier.

FIG. 6 is a right side view thereof.

FIG. 7 is a left side view thereof; and,

FIG. 8 is a bottom view thereof.

Dashed lines in FIGS. 1-8 illustrate environment in the form of additional rings and an additional graspable loop of the bottle carrier into which the claimed design can be incorporated, and thus form no part of the claimed design. In FIGS. 1-8, two rings and a graspable loop are shown and claimed in solid lines; however, it will be appreciated that additional disclosed features, such as additional rings and/or an additional graspable loop, may be later claimed in this or a related application. Additional dashed lines in FIG. 5 illustrate environment in the form of a hand shown grasping loops of the bottle carrier, and bottles secured within rings of the bottle carrier. The dashed lines illustrating the hand and bottles in FIG. 5 also form no part of the claimed design.
